UNITED STATES PATENT OFFICE.

GEORGE F. MATTESON, OF ROCKYHILL, CONNECTICUT, ASSIGNOR TO THE F. B. SHUSTER COMPANY, OF NEW HAVEN, CONNECTICUT, A CORPORATION OF CONNECTICUT.

WIRE-CUTTING MACHINE.

Application filed October 20, 1927. Serial No. 227,473.

My invention relates to the class of machines employed for cutting wire into certain lengths and an object of my invention, among others, is to obtain a mechanism for receiving the severed lengths of wire and for discharging said lengths, said mechanism being of simple construction and efficient in operation.

A portion of one form of machine embodying my invention and in the construction and use of which the objects herein set out, as well as others, may be attained, is illustrated in the accompanying drawings, in which—

Figure 1 is a view in side elevation of one end of a wire straightening and cutting machine illustrating my improved mechanism connected therewith.

Figure 2 is an end view of the structure shown in Figure 1, with parts broken away to show construction.

Figure 3 is a view in section of the upper portion of the structure on a plane denoted by the dotted line 3—3 of Figure 1.

Figure 4 is a view of a portion of the machine shown in Figure 1 and illustrating a modified form of connection between the rock and releasing shafts.

Figure 5 is a view similar to Figure 2, but showing this modified form of connection.

Figure 6 is a view similar to Figure 3 and showing said modified form of connection.

Figure 7 is a perspective view showing this connection.

While my invention is not limited to use in connection with any special type of wire cutting machine, yet as it finds ready adaptation in connection with a wire straightening and cutting machine, I have illustrated such herein for the purpose of explaining my invention, in which drawings the numeral 5 indicates the base of a wire straightening and cutting machine, 6 a standard rising therefrom, 7 a cam shaft having one end rotatably supported in said standard and having a cam 8 for operating a shifting lever 9 employed to operate a sliding member 10 mounted for reciprocating movement in a bearing 11, the sliding member supporting a stationary cutting die and a cutter head 12 rotatably mounted on said member and having a movable cutting die to cooperate with said stationary cutting die. The member 10 has a lengthwise opening through which a wire 13 extends that may be delivered from a straightening mechanism in a manner common to machines of this class. The cutter carrier or sliding member 10 is

reciprocated by the lever 9 in order that the cutters may move with the wire while a length is being severed by said cutters. All of the mechanism thus far described is of old and well known construction and further illustration and description thereof are omitted herein.

The oscillating member of the cutters is operated as by means of a toothed segment 14 rigidly connected with said member and having its teeth meshing with the teeth of a segment 15 on the end of a cutter actuating lever 16 secured to one end of a rock shaft 17 mounted in bearings on the frame including the standard 6. The lever 16 is actuated by a bar 18 pivotally attached at its upper end to said lever and having a roller 19 at its lower end engaged within a cam groove in a cam 20 secured to and operated by the cam shaft 7.

The wire receiving mechanism comprises 75 a frame including standards 21, one only of which is shown herein, it being understood that there will be two or more of these structures to support the opposite ends of members shown herein as supported at one end 80 by the standard 21. These standards may be connected as by means of a supporting bar 22 secured to and extending from the standard 6.

A box 23 in the form of a bar with a groove 85 in its under surface is secured to the under side of brackets 24 extending upwardly from the upper ends of the standards 21 and a wire rest 25 is movably mounted to close the open side of the groove in the box, as shown 90 herein this opening being in the under side of the bar constituting the box. This rest is secured to the upper sides of supporting arms 26 secured to and projecting from a releasing shaft 27 mounted for rocking 95 movement in bearings on the brackets 24, and as shown in Figure 2 of the drawings. A lever 28 is secured to and projects from the supporting arm 26 located at that end of the shaft 27 nearest the standard 6. This 100 lever 28 is operatively connected with an actuating arm 29 secured to a projecting end of the shaft 17. The connection between the lever 28 and arm 29 may be of any suitable construction to permit rocking movement of the two members, as herein shown a block pivoted on the arm 29 being located in a slot in the end of the lever 28, and as shown 105 in Figure 3 of the drawings.

From this description, taken in connection 110

with the accompanying drawings, it will be noted that the mechanism for releasing a severed length 30 of wire is operated simultaneously with and by the mechanism for 5 operating the cutters.

The wire rest 25 is located in the position shown in Figure 2 while the wire is being projected through the cutters and before it is severed, the rest in connection with the 10 box therefore serving as a guide for the wires. Upon the downward movement of the bar 18 to operate the cutters to sever a piece of wire the connections between the rock shaft 17 and the supporting arms 26, 15 hereinbefore described, causes the latter to be withdrawn and remove the wire rest from the trough in the box, and the severed length of wire 30 is permitted to fall onto a support constituted by a curved edge of the 20 standards 21 and swinging jaws 32 pivotally supported on the standards 21 and operated by means of a rod 33 extending to a treadle operated mechanism (not herein shown but which is of old and well known construction). A lip 31 on the end of the wire rest 25 serves to guide the wire into the trough in the box 23.

While the lever 28 and the arm 26 are shown herein as integrally formed, it is obvious 30 that they may comprise two separate pieces detachably connected if desired.

In the structure shown in Figures 4 to 7 inclusive I have provided means for placing and retaining the supporting arms 26 35 so that the rest 24 may be removed from the mouth of the box 23 when desired and for operating the machine as thus arranged when occasion may demand. To this end the supporting arms 26 are secured to the releasing shaft 27 and a connecting block 34 is 40 loosely mounted on the shaft, as clearly shown in Figure 7. This block has a locking notch 35 in its end to receive a locking lug 36 projecting from one side of a locking head 37. A retaining lug 38 projects from the opposite side of said head in position to engage a retaining notch 39 formed in the top of the standard 21. The head 37 is pivotally mounted in a notch in the upper end 45 of one of the supporting arms 26, which arm is extended a short distance above the shaft, as shown in Figure 7 of the drawings. The head is adapted to have a rocking movement in the slot in the lever 26, as by means of an 50 operating handle 40 that is removably attached to the head 37 for this purpose. By this arrangement of parts the arm 26, in which the head 37 is mounted, is adapted to 55 be locked either to the block 34 or to the standard 21. When not in use such handle 60 may be placed in a socket 41 in the standard.

The head 37 is yieldingly retained in either of its locking positions, as by means of a spring pressed detent 42 in the arm 26 65 projecting to engage either one of two

notches 43 in the under side of the head, and as shown in dotted lines in Figure 4 of the drawings.

In the use of the device in this form when it is desired to operate the machine to retain 70 the wires in the box 23 until they are cut off the lug 36 is engaged in the notch 35, as shown in Figure 7 in which position the machine will operate as hereinbefore described with respect to the machine shown in Figures 1 to 3 through the medium of the arm 75 28 that is rigidly connected with the block 34 and is engaged with the actuating arm 29 in the same manner as hereinbefore described with respect to the device of Figures 1 to 3. 80

If it be desired to uncover the opening in the box 23 to retain the box thus uncovered for any reason, the head 37 is swung, as by means of the handle 40, from the position shown in Figure 7 to a position to disengage 85 the lug 36 from the notch 35. Said handle is then made use of to swing the arm 26 thus rotating the shaft 27 independently of the block 34 and to a position so that the lug 38 may be engaged with the locking notch 39, in 90 which position of said arm the rest 25 will be removed to uncover the opening in the box, and the machine may be operated if desired with the parts in this position.

In accordance with the provisions of the 95 patent statutes I have described the principles of operation of my invention, together with the apparatus which I now consider to represent the best embodiment thereof; but I desire to have it understood that the device 100 shown is only illustrative, and that the invention may be carried out by other means and applied to uses other than those above set out.

I claim—

1. A wire cutting machine including a cutter, a box to receive a severed length of wire from said cutter, a wire rest pivotally supported to close an opening into said box, means for operating said cutter, and a connection between said cutter operating means and said wire rest for pivotally moving the latter in opposite directions. 110

2. A wire cutting machine including a cutter, a trough shaped box having a downwardly opening recess to receive a severed length of wire from said cutter, a wire rest movably supported underneath said box to close said opening, means for operating said cutter, and a connection between said cutter operating means and said wire rest for moving the latter positively into both of its operative positions. 115

3. A wire cutting machine including a cutter, a box to receive a severed length of wire from said cutter, a wire rest movably supported to close the opening into said box, means for operating said cutter, and a connection between said cutter operating means and said wire rest for positive operation of 120 125 130

the latter to release a length of wire from the box during cutting movement of the cutters and to return said wire rest in position to close the box during a reverse movement of the cutters.

4. A wire cutting machine including a cutter, cutter operating mechanism including a rock shaft, means for operating said rock shaft, a box to receive a severed length of wire from said cutter, a wire rest movably supported to close an opening into said box, and a connection between said rock shaft and said wire rest for operation of the latter.

5. A wire cutting machine including a cutter, cutter operating mechanism including a toothed member rigidly connected with the cutter member, a rock shaft, a lever secured to said rock shaft and having a toothed end meshing with said toothed member, means for operating said lever, a box to receive a severed length of wire from said cutter, a wire rest movably supported to close an opening into said box, and a connection between said rock shaft and wire rest for operation of the latter.

6. A wire cutting machine including a cutter, a box to receive a severed length of wire from said cutter, a wire rest movably supported to close an opening into said box, a series of arms to support said rest, a releasing shaft to which said arms are secured, means for operating said cutter, and a connection between said cutter operating means and said releasing shaft for operation of the latter.

7. A wire cutting machine including a cutter, a box to receive a severed length of wire from said cutter, a wire rest movably supported to close an opening into said box, a series of arms to support said wire rest, a releasing shaft to which said arms are secured, an actuating lever mounted on and projecting from said shaft, cutter operating mechanism including a rock shaft, and a connection between said arms and said rock shaft for operation of the former by the latter.

8. A wire cutting machine including a cutter, a box to receive a severed length of wire from said cutter, a wire rest movably supported to close an opening into said box, a series of arms to support said wire rest, a releasing shaft to support said arms, an actuating lever mounted on and projecting from said shaft, cutter operating mechanism including a rock shaft, means for operating said rock shaft, and an arm secured to and projecting from said rock shaft and in operative engagement with said actuating lever.

9. A wire cutting machine including a cutter frame, a cutter mounted on said frame, cutter operating mechanism including a rock shaft projecting beyond the end of the frame, a wire receiving frame spaced a slight dis-

tance from said cutting frame, a releasing shaft operatively mounted on said wire receiving frame, an operative connection between said rock shaft and said releasing shaft, said connection being located between said frames, a box to receive a severed length of wire from said cutter, a wire rest movably supported on said wire receiving frame to close an opening into said box, and a connection between said wire rest and said releasing shaft for operation of the former by the latter.

10. A wire manipulating machine including a box, means for supplying pieces of wire to said box, a wire rest to cover an open side of said box, a support for said rest, an actuator, means for operating said actuator, and means for coupling said support with and for uncoupling it from said actuator.

11. A wire manipulating machine including a box, means for supplying pieces of wire to said box, a wire rest to cover an open side of said box, a supporting shaft, a supporting member for said rest and an actuating member, one of said members being secured to said shaft and the other being freely rotatable thereon, means for operating said actuating member, and means for coupling said support with and for uncoupling it from said actuator.

12. A wire manipulating machine including a box, means for supplying pieces of wire to said box, a wire rest to cover an open side of said box, a supporting shaft, a rest support secured to said shaft, an actuator loosely mounted on the shaft, means for operating said actuator, and means for coupling said support with and for uncoupling it from said actuator.

13. A wire manipulating machine including a box, means for supplying pieces of wire to said box, a wire rest to cover an open side of said box, a support for said rest, an actuator, means for operating said actuator, means for coupling said support with and for uncoupling it from said actuator, and means for locking said support in a position to uncover the opening into the box.

14. A wire manipulating machine including a box, means for supplying pieces of wire to said box, a wire rest to cover an open side of said box, a supporting shaft, a supporting member for said rest and an actuating member, one of said members being secured to said shaft and the other being freely rotatable thereon, a head rockingly mounted in one of said members and having a detent to engage a locking notch in the other member, and means for operating said actuator.

15. A wire manipulating machine including a box, means for supplying pieces of wire to said box, a wire rest to cover an open side of said box, a supporting shaft, a supporting member secured to said shaft, an actuating member loosely mounted on said shaft, a

head rockingly mounted on said supporting member and having a detent to engage a notch in said actuating member and a locking detent, means to receive said locking detent to lock said support in a predetermined position, and means for operating said actuator.

16. A wire cutting machine including a cutter, a box to receive a severed length of wire from said cutter, a wire rest to cover an open side of said box and to receive severed lengths of wire therein, a support for said rest, an actuator, an operative connection between said actuator and said wire cutting mechanism, and means for coupling said support with and for uncoupling it from said actuator.

17. A wire working machine including a wire receiving box, a wire rest movably supported to close an opening into said box, and a lip formed on the wire rest at the receiving end of the box for guiding the wire into the latter.

18. A wire cutting machine including a rotatable cutter, a box to receive a severed

length of wire from said cutter, a wire rest 25 pivotally supported to close an opening into said box, a common operator element, and connections between said element and the cutter and wire rest for causing simultaneous rotation of the cutter and pivotal 30 movement of the wire rest in opposite directions.

19. In a wire working machine, a box to receive a length of wire, a wire rest to close an opening into said box, a rock shaft, and an 35 arm and lever connection between the rock shaft and the wire rest for causing rocking movement of the shaft to oscillate the rest into its closed and opened positions.

20. A wire working machine including a 40 box to receive a length of wire, a wire rest to close an opening in said box, a rock shaft parallel with the box, a plurality of arms connected to the rock shaft and the wire rest at spaced intervals along the same, and means 45 for operating the rock shaft to pivot the wire rest in opposite directions.

GEORGE F. MATTESON.
